LIFTING JACK

Application filed October 19, 1926, Serial No. 142,679, and in Germany October 21, 1925.

Our invention relates to lifting jacks for motor cars and the like and it is an object of our invention to provide a jack of the kind described which is so designed as to be able to operate permanently under unfavourable conditions, for instance, in water or in miry ground. To this end we so arrange the worm gear or other part the rotation of which is changed into parallel motion of a plunger or the like that it closes tightly the casing of the jack and imparts not only parallel but also rotary motion to the plunger so that any impurities and the like are stripped from the plunger by the combined rotary and parallel motion, and we so arrange the means for operating the plunger, for instance, the worm gear, that the worm gear is entirely relieved from thrust and the stress exerted on the gear results exclusively from tooth reaction.

In the drawings affixed to this specification and forming part thereof a lifting jack embodying our invention is illustrated diagrammatically by way of example.

25 In the drawings

Fig. 1 is a longitudinal section along the axis of the jack,

Fig. 2 is a corresponding section illustrating its plunger separately,

30 Figs. 3, 4 and 5 are sections on the corresponding lines of Fig. 2,

Fig. 6 is an elevation, and

Fig. 7 is an end elevation of a control rod inserted in the jack,

35 Fig. 8 is an end elevation, and

Fig. 9 is a side elevation of the boss of the worm gear for rotating the plunger, with the rim broken away.

Referring now to the drawings, *b* is the 40 tubular casing of the jack, and *a* is a threaded spindle which is arranged concentrically in the tube and secured therein at one end by a boss *a*¹ which is screwed into the tube and held against rotation by a pin *c*. *d* is a 45 plunger which is threaded at one end and seated on the spindle *a*. Its threaded end extends as far as *d*' the remaining portion of the plunger being without a thread on the inside but fitting exactly the crest of the spindle threads. On the outside, the plunger

is shaped to a prismatic section *d*², for instance octagonal, as shown in Fig. 4.

f is a worm gear the boss *f*¹ of which is seated on the octagonal portion *d*² of the plunger *d*. *n* is a worm which meshes with the worm gear *f*', *f*² is a packing and wiping ring on the plunger *d* which abuts against the boss of the worm gear *f* at its outer end. *e* is a casing which is secured air-tightly on the tube *b* and adapted to receive the means for rotating the worm gear, not shown. It will be understood that instead of worm gearing, any other suitable means might be provided for imparting rotation to the plunger *d*. The boss *f*¹ of the worm gear *f* is cylindrical on the outside so as to form a continuation of the tubular casing *b* and is abutted at one end against the tubular casing. The casing *e* is flanged for the reception of the tubular casing *b* at one end, and at its other end it is abutted against the body of the gear *f* by means of a re-bent collar *e*¹ which makes air-tight connection at the boss and the body of the worm gear.

When the gear *f* is rotated the plunger *d* will rotate with it and at the same time will be displaced axially in the octagonal cavity of the boss *f*¹. Penetration of water or impurities of any kind to the working parts of the jack are prevented by the tight-fit of the boss *f*¹ on the prismatic portion of the plunger and by the casing *e* which surrounds the worm gear *f*.

The rotation of the plunger with respect to the object to be lifted is permitted by a rotatable head which is secured on the outer end *d*³ of the plunger *d*. The end may be tapered as shown, or cylindrical and provided with a cap *g* which is secured air-tightly on the end and provided with a washer *h* engaging a circling groove in the plunger *d*. If required, the cap may be re-bent from the washer *h* and provided with a flange *g*¹ at its outer end. The thrust of the plunger is transferred to the cap *g* by a spherical thrust bearing *i*' *i*² in the end *d*³ of the plunger.

If it is desired to apply the jack to inclined faces a rubber cushion is inserted in the cap *g* which may consist of a compara-

tively hard part k^1 at the centre and an annular part k^2 surrounding the central part k^1 . Obviously the cushion may be combined from any number of parts which may be arranged as desired, or it may consist of a single part of uniform material. In a cushion consisting of harder and softer parts the several parts constitute a single unit but at the same time are able to be displaced with regard to each other enabling them not only to transmit considerable forces but also to absorb the lateral forces which are so detrimental to a jack.

The principal advantage of our novel arrangement is constituted by the fact that the thrust of the jack is exerted on a single thrust bearing and the worm gear f is entirely relieved from thrust so that the only forces acting thereon are constituted by the tooth reaction. Another important advantage is due to the arrangement of the worm gear f which is adapted to rock freely about a stationary spindle and a reciprocating prismatic plunger which eliminates the necessity of splining and corresponding weakening of the parts so that the amount of material required is a minimum.

All working parts of the jack and particularly the screw spindle a are encased by air-tight means as described, and protected from access of impurities and the like in any relative position. The boss f^1 which, as mentioned, is tightly seated on the prismatic portion d^2 of the plunger, acts as a stripper for removing impurities from the plunger when the latter is retracted.

In some cases, for instance when the jack is used for lifting carriages or for tipping, it is necessary to provide an automatic control for its drive. In such cases a rod l is inserted air-tightly in an axial bore of the spindle a and projects from the boss a^1 . Its other end is provided with a disk m which fits exactly the bore of the plunger d . When the plunger d has been moved to the end of its stroke the shoulder d^1 of its threaded portion will engage the disk m as shown in dotted lines in Fig. 2 and displace the rod l axially. This displacement is transmitted to a control of any suitable type which is preferably operated electrically. On the return motion of the plunger the block i' of the bearing in the hollow end d^3 will return the rod l to its initial position.

This air-tight arrangement of the rod l within the jack and the stationary spindle a is a result of the rocking arrangement of the worm gear f which enables the entire thrust of the jack to be distributed concentrically to the disk m and the rod l .

We wish it to be understood that we do not desire to be limited to the exact details of construction shown and described for obvious modifications will occur to a person skilled in the art.

We claim:—

1. A lifting jack comprising a base, a threaded spindle on said base, a tubular plunger on said spindle having a threaded part adapted to engage the thread of said spindle, a prismatic seat on the outside of said plunger, a casing secured to said base and surrounding the lower part of said plunger so as to guide it, a wheel tightly fitting said prismatic seat and adapted to rotate with respect to said casing, and means for rotating said wheel.

2. A lifting jack comprising a base, a threaded spindle on said base, a tubular plunger on said spindle having a threaded part adapted to engage the thread of said spindle, a prismatic seat on the outside of said plunger, a casing secured to said base and surrounding the lower part of said plunger so as to guide it, a wheel tightly fitting said prismatic seat and adapted to rotate with respect to said casing, means for rotating said wheel, and a guard surrounding it.

3. A lifting jack comprising a base, a threaded spindle on said base, a tubular plunger on said spindle having a threaded part adapted to engage the thread of said spindle, a casing secured to said base so as to surround and guide said plunger, a resilient cushion at the outer end of said plunger, two members having spherical surfaces forming a thrust bearing intermediate said cushion and said plunger, a cap having an inner wall surrounding said thrust bearing and an outer wall enclosing said resilient cushion, and means for imparting rotary motion to said plunger.

In testimony whereof we affix our signatures.

JOSEPH KLEE.
ALFONS SCHNEIDER.
